REED SWITCH FOR ELECTRICAL COMPONENTS

Bernard Edward Shlesinger, Jr., 3906 Bruce Lane,
Annandale, Va. 222203

Original design application Aug. 20, 1968, Ser. No.
13,198. Divided and this application Feb. 25, 1969,
Ser. No. 15,902

Term of patent 14 years

Int. Cl. D13—03

U.S. Cl. D26—13

FIGURE 1 is a front elevational view of a reed switch for electrical components showing my new design;

FIGURE 2 is a right side elevational view thereof;

FIGURE 3 is a left side elevational view thereof;

FIGURE 4 is a top plan view thereof;

FIGURE 5 is a bottom plan view thereof;

FIGURE 6 is a front elevational view of a modified form of the reed switch for electrical components described in FIGURE 1 showing my new design;

FIGURE 7 is a right side elevational view thereof;

FIGURE 8 is a top plan view thereof;

FIGURE 9 is a bottom plan view thereof;

FIGURE 10 is a front elevational view of a modified form of the reed switch for electrical components described in FIGURE 1 showing my new design;

FIGURE 11 is a right side elevational view thereof;

FIGURE 12 is a top plan view thereof;

FIGURE 13 is a bottom plan view thereof.

The sides opposite to the sides shown in FIGURES 1, 6, 10 and 11 are identical to these respective figures.

This is a division of design application Ser. No. D. 13,198, filed Aug. 20, 1968.

I claim:

The ornamental design for a reed switch for electrical components, as shown and described.
